UNITED STATES PATENT OFFICE

158,165

RADIO RECEIVING SET

Denis F. White, Indianapolis, Ind.

Application July 21, 1948, Serial No. 147,697

Term of patent 14 years

(Cl. D56—4)

To all whom it may concern:

Be it known that I, Denis F. White, a citizen of the United States of America, residing at 1524 East Washington Street, Indianapolis, Indiana, have invented a new, original, and ornamental Design for a Radio Receiving Set, of which the following is a specification, reference being had to the accompanying drawing, forming a part thereof.

Fig. 1 is a side elevational view of a radio receiving set embodying my new design;

Fig. 2 is a rear elevational view thereof;

Fig. 3 is a front elevational view thereof;

Fig. 4 is a top plan view thereof; and

Fig. 5 is a view in vertical section on the line 5—5 in Fig. 1.

I claim:

The ornamental design for a radio receiving set, substantially as shown.

DENIS F. WHITE.
